(57) **CLAIM**

The ornamental design for a luggage cart, as shown.

DESCRIPTION

FIG. 1 is a perspective view of a luggage cart, showing my new design;

FIG. 2 is a right side elevational view thereof;

FIG. 3 is a front elevational view thereof;

FIG. 4 is a top plan view thereof;

FIG. 5 is a bottom plan view thereof; and,

FIG. 6 is a perspective view thereof showing an enlarged top perspective view, bottom perspective view, and side view of the encircled top element for clarity.

The broken line showing of the wheels and elements on the bottom of the cart is included for the purpose of illustrating the environment and forms no part of the claimed design.

A portable cart used for transporting luggage and the like.

1 Claim, 6 Drawing Sheets
